UNITED STATES PATENT OFFICE.

OTTO JOHNE, OF BAUTZEN, GERMANY.

CUTTING-MACHINE.

1,131,706.

Specification of Letters Patent. Patented Mar. 16, 1915.

Application filed April 21, 1913. Serial No. 762,657.

To all whom it may concern:

Be it known that I, OTTO JOHNE, a citizen of the German Empire, and residing at Bautzen, Germany, have invented certain new and useful Improvements in Cutting-Machines, of which the following is a specification.

Paper cutters provided with automatic pressers which need not be adjusted for various heights of paper to be cut, are known to the art. But such machines can hardly be termed practical, as the tension of the automatic presser becomes greater as the knife enters the paper and obtains its greatest tension when the knife has finished its cutting operation. The disadvantage of the foregoing is apparent, since the presser has not been clamped sufficiently upon the paper before the cutting operation to insure a straight or uniform cutting edge. Applicant overcomes the above objections in providing an arrangement whereby the presser has been clamped upon the paper to its greatest extent before the knife enters the paper and the tension exerted upon the presser and consequently the paper is uniform throughout the entire cutting operation of the knife.

One illustrative embodiment of my invention is represented by way of example in the accompanying drawings, wherein:

Figure 1 is a front elevation of a machine according to my invention, Fig. 2 is a cross-section taken on the bent line A—A in Fig. 3, and Fig. 3 a sectional plan.

Referring to the drawing, fast on the shaft 9 are the crank-disks 10, 11, whose pins 12 engage in known manner the connecting-rods 13 for the knife-carrier 3. Inside the walls of the frame and on the right and left hand sides the shaft 9 carries fast on it the gears 14 which mesh with the gears 7, the latter being provided with eccentrically mounted pins 15 and coupled with the yoke or bar 5 by means of draw-rods 6. A sleeve 4 is journaled on the shaft 9 and is provided with arms 16 and 17. The arms 16 at the ends of this sleeve are connected to the connecting-rods 8 for the cutter-beam 2. The yoke or bar 18 engages the middle arms 17. Between the bars 5 and 18 are located the springs 1 which are held together by means of the stay-bolts 19. When the crank-disk

10 is rotated in the direction indicated by the arrow, the wheels 14 and 7 are rotated. The draw-rods 6 connected to the wheels 7 therefore impart to the bar 5 a horizontal reciprocating motion, and to the beam 2, which is connected to the bar 5 by the rods 8, the sleeve 4 and the springs 1 a vertical reciprocating motion. By suitably adjusting the pin 12 for the knife-carrier 3 and the pin 15 for the beam 2 it can be arranged that during the first quarter revolution the springs 1 are given their maximum compression and compress the pile of paper, while during the next quarter revolution the springs are kept at their maximum compression when the knife is cutting the pile of paper. When the very heavy knife-carrier 3 and beam 2 move upward the energy stored in the springs 1 is advantageously used, so that consumption of power is saved.

I claim:

1. A paper cutting machine, comprising in combination, an automatic spring actuated paper presser, a positive knife cutter adjacent said presser, said presser adapted to compress the paper before and during the operation of the knife, and serving to help raise the knife to inoperative position.

2. A paper cutting machine comprising in combination, an automatic spring actuated paper presser, a positive knife cutter, said presser adapted to compress the paper before and during the operation of the knife, said paper presser actuated by springs, one end of said springs adjacent a shaft and the other end secured in a yoke which is secured to a driving means attached to said shaft and the presser, substantially as described.

3. A paper cutting machine comprising in combination, a frame, an automatic spring actuated paper presser, a positive knife cutter adjacent said presser, a shaft revolubly mounted in said frame, a connection between said cutter and said shaft adapted to actuate said cutter, a horizontally disposed spring secured to said frame, gears carried by said shaft, and means connecting said gears to said spring and said presser, said means serving to simultaneously compress said spring and presser, simultaneously with the depression of said cutter, substantially as described.

4. A cutting machine comprising in com-

bination, an automatic presser adapted to non-adjustably compress various size stacks of material, a cutter adjacent said presser, said presser and cutter adapted to be simultaneously actuated, said presser adapted to exert maximum pressure on the material before said cutter enters the material and adapted to exert a uniform pressure during

the cutting operation, substantially as described. 10

In testimony whereof, I affix my signature in the presence of two witnesses.

OTTO JOHNE.
